UNITED STATES PATENT OFFICE.

JAMES W. WILSON, OF TULSA, OKLAHOMA.

VALVE-GRINDER.

1,134,362.

Specification of Letters Patent. Patented Apr. 6, 1915.

Application filed January 11, 1915. Serial No. 1,634.

To all whom it may concern:

Be it known that I, JAMES W. WILSON, a citizen of the United States, residing at Tulsa, in the county of Tulsa and State of Oklahoma, have invented certain new and useful Improvements in Valve-Grinders, of which the following is a specification, reference being had to the accompanying drawings.

10 This invention relates to new and useful improvements in valve grinders and more particularly to a multiple valve grinder, the main object of the present invention being the provision of a valve grinder consisting 15 of a plurality of valve actuating members and means for imparting simultaneous rotary movement to the same.

Another object of the present invention is the provision of a device of the above character which will possess advantages in points 20 of efficiency and durability, is inexpensive to manufacture and, at the same time is simple in construction and operation.

With the above and other objects in view, 25 the invention consists in the novel features of construction, combination and arrangement of parts as will be hereinafter referred to and more particularly pointed out in the specification and claims.

30 In the accompanying drawings forming a part of this application, Figure 1 is a top plan view of a valve grinder constructed in accordance with my invention. Fig. 2 is a front elevation; and Fig. 3 is a transverse 35 sectional view.

Referring more particularly to the drawings, the numeral 1 indicates two spaced standards connected by means of a longitudinal member 2, said longitudinal member 40 being suitably brace adjacent its ends by means of the angular brace pieces 3. Extending transversely through the ends of the cross pieces 4 of the supporting members 1, are pivot pins 5, the inner ends of which 45 extend through the transverse supporting beams 6 of the movable frame which supports the operating mechanism. From this it will be apparent that the frame which supports the operating mechanism may be 50 readily raised and lowered and, when lowered will rest upon the longitudinal member 2. Supported upon the cross beams 6, are the spaced longitudinal beams 7, said beams being integrally connected by means 55 of the top pieces or blocks 8.

Mounted upon the upper faces of the beams 7 at the medial portions thereof, are the bearings 9 in which is mounted the shaft 10 and mounted upon this shaft is a pulley 11 connected by means of a belt 12 to a second pulley 13 disposed between the beams 7 and arranged beneath one of the blocks 8. This pulley 13 is mounted upon a transverse shaft 14 which is mounted within suitable bearings formed in the beams 7 and one end 60 thereof projects beyond the outer side wall of one of the beams and mounted thereon is a second pulley 15 to which is eccentrically connected a pitman 16, the purpose of which will be hereinafter more fully set forth. In 65 order to impart a reciprocating movement to the pitman 16, I provide a crank arm 17 which is secured to the outer end of the shaft 10 and provided with a handle 18, whereby the shaft 10 may be readily rotated 70 when it is desired to impart reciprocating movement to the pitman 16.

Secured to the outer face of one of the beams 7, are the spaced guides 19 and movable therein is a block 20, the outer edge of 80 which is connected to a reciprocating rack bar 21, while one end thereof is connected to the pitman 16 so that as the pitman 16 is reciprocated, the block 20 and bar 21 will be actuated simultaneously. This rack bar 85 21 is slidably mounted within suitable guide openings 22 formed within the end beams 6 and the teeth which are formed upon the outer edge thereof are adapted to mesh with the gears 23 carried by the upper ends of the 90 rotating shafts 24. The shafts 24 are rotatably mounted within suitable blocks 25 which are adjustably mounted upon a guide plate 26 and the shafts themselves are movable within a slot 27 formed within the plate 95 26 so that the blocks 25 may be readily adjusted longitudinally upon the plate 26, according to the character of the engine upon which the device is to be used. Mounted 100 upon the shafts 24, are the coil springs 28 which are disposed between the transverse pins 29 and the blocks 25, whereby to securely retain the gears 23 down against the upper face of the blocks so that it will, at all 105 times, remain in engagement with the teeth of the rack bar 21.

The blocks 25 are adjusted longitudinally upon the plate 26 and are securely held in position by means of set screws 30 which are carried by each of the blocks and are adapted for engagement with the plate 26. The lower ends of the shafts 24 are bifurcated and arranged therein, are the valve engaging tools 31 which may be of any general well known type and which will be rotated simultaneously with the reciprocation of the bar 21.

It will be apparent that in arranging this device in position to be used, the frame which supports the operating mechanism is raised and the supporting members 1 placed at each end of the engine and, after the supporting frame has been placed in position, the frame which supports the operating mechanism will be lowered so that the members 21 will be in a position to engage with the valves of the engine. After these have been placed in position, the crank 17 is actuated to rotate the shafts 10 and 14 which, in turn, will impart reciprocating movement to the pitman 16 and the rack bar 21. From this it will be apparent that all of the valves of the engine may be simultaneously ground upon operation.

It will further be apparent that the blocks 25 may be readily adjusted longitudinally upon the plate 26, so as to adapt the device to different kinds of engines.

It will also be apparent that the device is extremely simple in construction and can be manufactured and placed upon the market at a comparatively low cost.

While I have shown and described the preferred form of my invention, it will be obvious that various changes in the details of construction and in the proportions may be resorted to for successfully carrying my invention into practice, without sacrificing any of the novel features or departing from the scope of the invention, as defined by the appended claims.

Having thus described this invention, what I desire to claim and secure by Letters Patent, is:—

1. A valve grinder including spaced standards, a longitudinal member connecting said standards, a movable frame hingedly connected to said standards and mounted upon the longitudinal supporting member, a plurality of valve engaging elements, and means for simultaneously actuating said elements.

2. A device of the class described including spaced standards, a longitudinal member connecting said spaced standards, a movable frame hingedly connected to the standards and adapted to be supported by the longitudinal member, a plurality of adjustable blocks carried by said frame, vertically disposed shafts mounted within said blocks, gear teeth formed upon the upper ends of

said shafts, and a reciprocating rack bar adapted to engage said gear teeth and simultaneously rotate the shafts.

3. A valve grinder including spaced standards, a supporting member connecting said standards, a movable frame consisting of longitudinally extending spaced beams, a guide plate provided with a longitudinal slot, cross beams connected to the ends of said beams and plate, a plurality of rotatable shafts adjustably mounted within the guide plate, and means supported by the spaced beams and having connection with said shafts to simultaneously rotate the same.

4. A valve grinder including a movable frame, means for supporting said frame, a plurality of vertically disposed shafts adjustably mounted upon said frame, gears carried by the upper ends of said shafts, valve engaging elements carried by the lower ends thereof, a reciprocating rack bar adapted to engage the gears on the shafts, a transverse shaft carried by the movable frame, a pulley carried by the shaft, a pitman having one end eccentrically connected to the pulley and its other end connected to the rack bar, and means for imparting rotary movement to the transverse shaft whereby to reciprocate the rack bar and simultaneously rotate the vertical shafts, as and for the purpose set forth.

5. A valve grinder including a movable frame, means for supporting said frame, a guide plate carried by said frame and provided with a longitudinal slot, supporting blocks adjustably mounted upon the plate, vertically disposed shafts extending through the blocks and the slot in the plate, valve engaging elements carried by said shafts, and means for simultaneously rotating said shafts, as and for the purpose set forth.

6. A valve grinder including a movable member, means for supporting said member, a guide plate carried by the movable member having a longitudinal slot therein, supporting blocks adjustably mounted upon said plate, vertically disposed shafts extending through the blocks and the slot in the plate, valve engaging elements carried by the lower ends of said shafts, transverse pins extending through the shafts adjacent the lower ends thereof, and coil springs mounted upon the shafts and disposed between the pins and the guide plate, as and for the purpose set forth.

7. A valve grinder including a movable member, means for supporting said member, a guide plate carried by the movable member having a longitudinal slot therein, supporting blocks adjustably mounted upon said plate, vertically disposed shafts extending through the blocks and the slot in the plate, valve engaging elements carried by the lower ends of said shafts, gears car-

ried by the upper ends of said shafts, trans-
verse pins extending through the shafts ad-
jacent the lower ends thereof, coil springs
mounted upon the shafts and disposed be-
5 tween the pins and the guide plates, and
means engaging the gears for simultaneously
rotating the shafts.

In testimony whereof I hereunto affix my
signature in the presence of two witnesses.

JAMES W. WILSON.
